BELT GUARD FOR A MILLING MACHINE HEAD

Gilbert N. Clay, 6576 White Doe Trail, Rockford, Ill.
61102, and Donn O. Smith, 302 Hosmer St., Loves
Park, Ill. 61111

Filed May 24, 1973, Ser. No. 363,520

Term of patent 14 years

Int. Cl. D15—99
U.S. Cl. D54—14 A

FIG. 1 is a perspective view of a belt guard for a milling machine head, the broken line showing of a portion of a milling machine head being only for the purpose of illustrating environment;

FIG. 2 is a top plan view of the belt guard for a milling machine head;

FIG. 3 is a front elevational view thereof;

FIG. 4 is a bottom view thereof;

FIG. 5 is a rear elevational view thereof;

FIG. 6 is an end elevational view thereof as viewed from the left in FIG. 3; and

FIG. 7 is an end elevational view thereof as viewed from the right in FIG. 3.

We claim:

The ornamental design for a belt guard for a milling machine head, substantially as shown and described.
